UNITED STATES PATENT OFFICE

113,480

DESIGN FOR A DRESS

Morris Preller, New York, N. Y.

Application January 17, 1939, Serial No. 82,382

Term of patent 3½ years

To all whom it may concern:

Be it known that I, Morris Preller, a citizen of the United States and a resident of the city of New York, in the county of Kings and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

I claim:

The ornamental design for a dress, substantially as shown.

MORRIS PRELLER.
